UNITED STATES PATENT OFFICE

CHARLES RAYMOND WASEIGE, OF RUEIL, FRANCE, ASSIGNOR TO HENRI ET MAURICE FARMAN, OF BILLANCOURT, FRANCE

STARTING DEVICE FOR INTERNAL COMBUSTION ENGINES

Application filed June 18, 1931, Serial No. 545,304, and in France July 8, 1930.

The object of my invention is a starting device operating by inertia for an internal combustion engine particularly adapted to be used in connection with an air-craft engine.

It is well known that the direct starting of an internal combustion engine requires the application of a powerful driving torque and accordingly necessitates a fairly considerable source of energy. Therefore, in the case of an electric starter, it is necessary to employ a fairly powerful motor, absorbing current of high amperage, which involves the use of strong batteries.

In order to avoid this disadvantage, devices have already been contrived allowing for the storing up, in a fly-wheel running at high speed, of a sufficient quantity of energy to insure, subsequently, the starting of the engine. These devices are provided with a fly-wheel connected to the engine to be started through a clutch. Said fly-wheel is actuated by a driving device through which it can acquire, when the clutch is disengaged, a sufficient kinetic energy to insure the starting of the engine once the clutch is let in.

A characteristic feature of my invention lies in the fact that the connection between the driving device and the engine to be started is such that the kinetic energy of the whole, or of the greater part, of the rotating parts of the driving device and of the transmission system interposed between the latter and the engine is added to that of the fly-wheel in order to insure the starting of the motor. This feature of my invention allows of reducing considerably the power required by the driving device.

When the driving device consists of an electric motor, a second characteristic feature of my device lies in the fact that the clutch is so combined with a device adapted to control the feeding of the motor, that the feeding circuit is automatically switched off when the connection is made. This prevents any risk of deteriorating the electric motor in case of an abnormal resistance of the engine to be started.

Preferred embodiments of my invention

will be hereinafter described with reference to the accompanying drawings given merely by way of an example and in which:

Fig. 1 is a sectional view of the electric motor and of its connection to the crank shaft of the internal combustion engine.

Fig. 2 is a similar view of another embodiment of my invention.

In Fig. 1, electric motor 1 drives fly wheel 2, which is keyed directly on its shaft, and it is connected to the crank shaft of the engine to be started through a suitable reduction gear and a clutch. The reduction gear comprises pinion 3, adapted to be automatically disconnected according to a known arrangement. Screw 4, on which said pinion is mounted, is free to rotate about its axis 5 and the pinion is braked by a frictional member 6, the support of which slides longitudinally in grooves 7 of the gear case. The clutch is so devised as to make it possible, when so desired, to impart the rotary motion of the electric motor to screw 4. To this effect, screw 4 is provided, at its extremity, with dogs which may be engaged by those of a sleeve 8, the latter being adapted to be rotated by shaft 5 through longitudinal grooves, so that it can slide on said shaft 5. The displacement of sleeve 8 is controlled by fork 9, which is itself actuated by a spring sliding rod 10, the whole device being so arranged that sleeve 8 will be normally disconnected. Sliding rod 10 is connected with a switch 17 which controls the feeding of electric motor 1, in such a manner that a traction exerted on the latter automatically switches off said feeding circuit.

The device works in the following manner:

In order to start the internal combustion engine, the electric current of a battery, or of any other source of electricity, is caused to flow through electric motor 1, without operating sliding rod 10. Motor 1 will then be running on no load, since it will only be driving the gear train, screwed pinion 3 excluded, so that the only resistance is due to friction. Under these conditions, motor 1 can attain a very high speed, thus storing

considerable energy in the moving parts. However, the feeding current is very soon limited to a very small intensity, since the motor runs on no load. By operating sliding rod 10, sleeve 8 is coupled with screw 4, so that the latter is caused to rotate, this bringing pinion 3 into mesh with the wheel keyed to the crank shaft and starting the internal combustion engine. Once said engine is started, pinion 3 is automatically disconnected, in the well known manner.

It may be seen that, under these conditions, most of the parts belonging to the transmission system provided between the 15 starter and the crank shaft, as well as the armature of said starter, are made use of, in addition to the fly wheel, for storing up energy under the form of kinetic energy, prior to coupling the starter and the engine 20 to be started.

Through the switch 17 the feeding current is automatically switched off as soon as sliding rod 10 is operated in order to connect sleeve 8 and screw 4. It should therefore be noted that the internal combustion engine is never driven directly by the electric starter, i. e., that the starter is never traversed by a current of high intensity, no matter what the resistance of the combustion 30 engine may be.

The embodiment shown in Fig. 2 comprises the same main parts as shown in Fig. 1, but the pinion drives counter shaft 11 instead of actuating directly a wheel keyed to the crank shaft to be started. That particular arrangement allows of operating said pinion under the conditions of speed and of transmitted torque most favorable to a good working. Counter shaft 11 is at 40 right angles to the axis of the crank shaft and drives the latter through bevel pinion 12, in mesh with disk 13, which is provided with conical teeth and keyed to crank shaft 2. Said counter shaft is moreover employed 45 to drive generator 14 by means of gear wheels 15 and 16.

While I have disclosed what I deem to be preferred embodiments of my device, it should be well understood that I do not wish 50 to be limited thereto as there might be changes made in the arrangement, disposition and form of the parts without departing from the spirit of my invention as comprehended within the scope of the appended 55 claim.

What I claim is:

In a starting device for internal combustion engines, in combination a crank shaft of 60 an internal combustion engine, a toothed wheel operatively connected with said crank shaft, an auxiliary shaft rotatably mounted, driving means adapted to rotate said auxiliary shaft, a screw loosely rotatable on said auxiliary shaft, an element rotatably connected to said auxiliary shaft and adapted to 65

slide thereon, coupling means on said element and on said screw adapted to cooperate together, means for controlling the above mentioned element so as to bring said coupling means in cooperating engagement, a pinion provided with internal screw threads 70 engaging said screw, and a stop member on said screw adapted to stop said pinion in a position in which it is in mesh with said toothed wheel and to lock it angularly in 75 said position with respect to the screw.

In testimony whereof I have signed my name to this specification.

CHARLES RAYMOND WASEIGE.
